UNITED STATES PATENT OFFICE.

JOHN A. PILCHER, OF ROANOKE, VIRGINIA.

CAR-TRUCK SIDE FRAME.

1,308,192.

Specification of Letters Patent.

Patented July 1, 1919.

Application filed December 22, 1917. Serial No. 208,410.

To all whom it may concern:

Be it known that I, JOHN A. PILCHER, a citizen of the United States, residing at Roanoke, in the county of Roanoke and 5 State of Virginia, have invented certain new and useful Improvements in Car-Truck Side Frames, of which the following is a specification.

This invention relates to car truck side 10 frames of the arch bar type and has for its object to provide improvements in the construction of such devices whereby metal may be saved and whereby the metal used may be employed to better advantage. The invention 15 consists of the formation, combination and arrangement of parts as will be herein described and claimed.

In the drawings, Figure 1 is a broken plan view of a side frame constructed in accordance with the present invention and 20 Fig. 2 a similar side elevational view of the same. Fig. 3 is a horizontal section thereof taken substantially on the line 3—3 of Fig. 2. Fig. 4 is a fragmentary section taken on 25 the line 4—4 of Fig. 1. Fig. 5 is a vertical section taken on the line 5—5 of Fig. 2.

Referring now to these drawings, the side frame consists of a top arch member 1 and a bottom arch member 2, these being vertically spaced apart at their centers with a 30 spring seat member 3 resting upon the bottom arch member and vertical columns or ties 4 located intermediate the ends of the frame and in spaced relation to each other 35 longitudinally of the frame, thereby providing a window opening therebetween. These ties extend upward to the top arch member and are secured thereto. The outer ends of the arch members converge and are 40 coactively secured together to form a truss, the oil boxes, such as 5, being secured to the ends of the frames. A spring plank 6 of the customary construction may be used to form a crosstie member for spacing the frames 45 when used on opposite sides of a truck, one of the features of the invention being the manner of connecting a spring plank of such or other construction to the spring seat member 3.

50 For co-actively securing the ends of the arch members together, the top member which is made of a structural channel, with the web horizontal and the flanges depending, is of less length than the bottom member, and the bottom arch member, which is 55 made of a steel bar, passes, near the ends of

the top arch member, between the flanges of the channel and against the lower face of its web. Just beyond the end of the channel the metal of the bottom arch member is 60 upset or distorted at 7 to form an abutment or seat for the end metal of the channel, the upset being both for the flanges and for the web. The original cross section of the metal of the bottom arch member is then carried 65 on outward at 8 to form a part of the securing means for the journal box 5 which is attached to the side frame by means of the longitudinally spaced, vertical box bolts 9. These bolts are disposed one to either side 70 of the upset metal 7, the outer bolt passing through the bottom arch member only and the inner one through both arch members.

The spring seat member 3 is made of pressed steel and includes a transverse bottom bearing face 10 shaped to conform to and bear upon the central upper face of the bottom arch member. From this bottom, substantially vertical side walls or flanges 11 rise and the central portions 12 of these 80 flanges are flared and flattened away from each other to form a flat spring seat. A spring plank such as 6 or its equivalent is riveted to these portions 12 and thus forms a tie across the open space between the two 85 side walls and these flat portions.

The side walls 11 at their ends extend upward in vertical planes and inserted between them are the lower ends of the columns 4. These columns are made of flanged or channel sections, the backs of the webs being turned toward each other and there being rivets passing through the upstanding flanges of the spring plank channel and the vertical webs of these columns. Securing 90 rivets also pass through the side walls 11 of the spring seat member and the lower ends of the flanges of the columns, thus forming not only vertical strength but also transverse strength. Each part thus serves to stay and 95 brace the other and is at the same time of light weight. At their upper ends the webs of the columns at 13 are bent at right angles away from each other to abut and underlie the bottom face of the top arch member. At 100 the same time the side flanges at 14 are carried upward and bent around over the back of the top arch member. Securing rivets then pass through the top arch member and through the underlying and the overlying 110 portions of the columns.

Secured to the adjacent inner faces of the

columns are vertical wear plates 15 which, at their upper ends are likewise bent to form knees to fit under the top arch member and are then riveted thereto, thus forming a substantial tie at the top. As the top and bottom arch members are preferably made of different widths, so the columns are similarly tapered from the top to the bottom.

I have thus described an embodiment of my invention. Other embodiments are possible within the scope of the appended claims without departing from the spirit of the invention.

I claim:

15. 1. In a car truck side frame, a pair of vertically spaced arch bars converging at their ends, oil boxes secured to the ends thereof, and an inner and an outer securing bolt for each box, the inner bolt passing through both of said arch members and the outer one through one only thereof.
20. 2. In a car truck side frame, a pair of vertically spaced arch bars converging at their ends, oil boxes secured to the ends thereof, and an inner and an outer securing bolt for each box, the inner bolt passing through both of said arch members and the outer one through the bottom arch member only.
25. 3. In a car truck side frame, a pair of vertically spaced arch members converging at their ends, one of said members extending outward at its ends for a greater distance than the other, said longer member having a distorted portion remote from its end for contacting and abutting the end of the shorter member, and in combination therewith an oil box, means for attaching the oil box to the end of the frame, said
30. 40. means embodying box-securing bolts which are spaced one from the other longitudinally of the frame and box and disposed one to either side of the distorted metal of the said arch bar.
35. 45. 5. In a car truck side frame, a pair of vertically spaced arch members converging at their ends, one of said members extending outward at its ends for a greater distance than the other, said longer member having a distorted portion remote from its end for contacting and abutting the end of the shorter member, and in combination therewith an oil box, means for attaching the oil box to the end of the frame, said means embodying box-securing bolts which are spaced one from the other longitudinally of the frame and box, the outer one passing through the side frame beyond the end of the shorter arch member and the inner one passing therethrough within the limits thereof.
50. 60. 6. In a car truck side frame, a pair of vertically spaced arch members converging at their ends, the lower arch member extending outward at its ends for a greater distance than the upper member, said lower

member having a distorted portion remote from its end for contacting and abutting the end of the upper member, and in combination therewith an oil box, means for attaching the oil box to the end of the frame, said means embodying box-securing bolts which are spaced one from the other longitudinally of the frame and box, the outer one passing through the outer end of the bottom arch member and the inner one passing through both arch members.

6. In a car truck side frame of the arch bar type, a spring seat member adapted to bear upon and conform to the bottom arch member, the same including a bottom bearing face with substantially vertical flanges rising from each side thereof, a portion of said flanges being flattened to form a horizontal spring seat, the said spring seat member being formed of a shaped steel plate and there being a member separate therefrom but attached thereto and extending to the top arch member.

7. In a car truck side frame of the arch bar type a spring-seat member formed of a shaped plate of sheet metal and adapted to bear upon and conform to the bottom arch member, the same including a bottom bearing face with substantially vertical flanges rising from each side thereof, the central portion of said flanges being flattened to form a spring seat and the end portions thereof forming column-attaching means, and separately formed column members attached thereto and extending to the top arch member.

8. In a car truck side frame of the arch bar type a spring-seat member adapted to bear upon and conform to the bottom arch member, the same including a bottom bearing face with substantially vertical flanges rising from each side thereof, the central portion of said flanges being flattened to form a spring seat and the end portions thereof forming column-attaching means, and columns disposed with their lower ends between the end portions of the said flanges and forming a tie therebetween.

9. In a car truck side frame of the arch bar type a spring-seat member formed of a shaped plate of sheet metal and adapted to bear upon and conform to the bottom arch member, the same including a bottom bearing face with substantially vertical flanges rising from each side thereof, the central portion of said flanges being flattened to form a spring seat and the end portions thereof forming column-attaching means, and a spring plank secured to and forming a tie between the said central portion of the said flanges.

10. In a car truck side frame, a pair of separate, vertically spaced arch members and a separate, intermediate, vertical tie member extending there-between, said tie

member having a transversely-disposed web with a flange along one of its edges, the web thereof being secured to the under face of the top arch member and the flange there-
5 of being secured to another face of the top arch member.

11. In a car truck side frame, a pair of separate, vertically-spaced arch members and a separate, intermediate, vertical tie member extending there-between, said tie member having a transversely-disposed web with a flange along one of its edges, the web thereof being secured to the under face of the top arch member and the flange thereof
10 being bent over and secured to the top face thereof.

12. In a car truck side frame, a pair of separate, vertically spaced arch members and a separate, intermediate, vertical tie member extending there-between, said tie member having a transversely-disposed web with flanges along its edges, the web there-
20 of being secured to the under face of the top arch member and the flanges thereof being bent around opposite edges of the top arch member and being secured to the top face of
25 the same.

13. In a car truck side frame, a pair of separate, vertically-spaced arch members, and a pair of separate, intermediate, vertical tie members extending there-between to form a window opening, said tie members having transversely-disposed webs with flanges along their edges, the tops of the
30 webs thereof being bent away from the center of the frame into angular portions disposed to underlie the top arch member, and the flanges thereof being bent around opposite edges of the top arch member to overlie
35 the same, and securing means passing through the top arch member and the said underlying and overlying portions of the tie members.

14. In a car truck side frame, a pair of separate, vertically-spaced arch members, and a pair of separate, intermediate, vertical tie members extending there-between to form a window opening, said tie members having transversely-disposed webs with
40 flanges along their edges, the tops of the webs thereof being bent away from the center of the frame into angular portions disposed to underlie the top arch member and

being secured thereto, there being wear plates secured to the opposing faces of the said columns, the same extending upwardly to the under face of the top arch member and being there bent into angular portions to abut said face and being also secured thereto.

15. In a car truck side frame, a pair of arch members one of which extends longitudinally of the frame for a greater distance than the other, a journal box, and bolts for attaching the box to the arch members, one
60 of said bolts passing through the extending end of the one arch member and another of the bolts passing through both arch members.

16. In a car truck side frame, a pair of arch members, a journal box, and bolts for attaching the box to the arch members, one of the same passing through but one of the arch members and another passing through
70 both of the arch members.

17. In a car truck side frame of the arch bar type, a top arch member of channel cross section disposed with the flanges depending and a bottom arch member provided with a separate, central portion having
75 upstanding flanges, and a separate, vertical tie member secured to said upstanding flanges and extending from therebetween to between the depending flanges at the top.

18. In a car truck side frame of the arch bar type, a top and a bottom arch member, one of which is of greater width than the other, and a separate vertical tie member extending there-between and tapered in width from one end to the other to agree
80 substantially with the corresponding widths of the arch members.

19. In a car truck side frame of the arch bar type, a top and a bottom arch member each of which are provided with portions
85 having flanges along their edges and these flanges being turned to extend toward each other, and a flanged tie member extending between the arch members, the flanges of the same being disposed on the inside faces
90 of the flanges of one arch member and on the outside faces of the flanges of the other arch member.

In testimony whereof I affix my signature.

JOHN A. PILCHER.
